[57] CLAIM

The ornamental design for snowman accessory kit, as shown and described.

DESCRIPTION

FIG. 1 is a perspective view of the snowman accessory kit showing my new design, the snowman shown in broken lines for illustrative purposes only;

FIG. 2 is a perspective view of a snowman, showing an example of how the parts of the kit of FIG. 1 may be combined with a snow sculpture, the latter being shown in phantom lines and forming no part of my design.
